CLAIM

The ornamental design for a planter lid as shown and described.

DESCRIPTION

FIG. 1 is a top perspective view of my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view shown in a position of use with a planter thereof.

The dash-dash broken lines showing a planter in FIG. 9 depict environmental subject matter that forms not part of the claimed design.

1 Claim, 9 Drawing Sheets
